RAILWAY SWITCH OPERATING APPARATUS

Herbert L. Bone, Forest Hills, Pa., assignor to The
Union Switch & Signal Company, Swissvale,
Pa., a corporation of Pennsylvania

Application March 2, 1937, Serial No. 128,645

19 Claims. (Cl. 246—284)

My invention relates to railway switch operating apparatus, and particularly to manually controlled switch operating apparatus for switches of the type which are designed to be trailed.

One object of my invention is to provide novel means whereby, when the movable rails of a switch of the type described are displaced from a set position by a trailing train, the rails will become biased to a position opposite to the set position until after the train has completely passed the switch, whereupon the rails will again become biased to their set position.

I will describe one form of apparatus embodying my invention, and will then point out the novel features thereof in claims.

In the accompanying drawings, Fig. 1 is a top plan view showing a railway switch provided with one form of switch operating mechanism embodying my invention. Fig. 2 is an enlarged side view, partly in section and partly in elevation, of the operating mechanism shown in Fig. 1. Fig. 2a is a view showing a target which forms part of the mechanism illustrated in Fig. 2. Fig. 3 is a top plan view, partly in section and partly in elevation, of the mechanism shown in Fig. 2. Fig. 4 is a longitudinal sectional view of the spring unit S¹ forming part of the mechanism shown in Figs. 2 and 3 taken on the line IV—IV of Fig. 3. Figs. 5, 6, 7, and 8 are sectional views taken substantially on the lines V—V, VI—VI, VII—VII, and VIII—VIII of Fig. 2. Fig. 9 is a view similar to Fig. 3 but showing the parts in the positions which they occupy while a train is trailing the switch. Fig. 10 is a diagram showing the various forces exerted on the switch points.

Similar reference characters refer to similar parts in each of the several views.

Referring first to Fig. 1, the reference character A designates a railway switch comprising, as usual, two fixed rails 1 and 1^a and two movable rails or switch points 2 and 2^a. The fixed rails 1 and 1^a are laid on tie plates 3 and are secured to crossties 4 in the usual manner. The movable rails 2 and 2^a are fastened together by a front rod 5, a head rod 6, a bridle rod 7, and a tie rod 8, and may be moved into a normal or a reverse position by means of an operating rod 9, which is connected with the head rod 6 through the medium of the usual switch basket 10. When the switch occupies its normal position, in which it is shown in Fig. 1, the movable rail 2 engages the fixed rail 1, and the movable rail 2^a is spaced a slight distance from the fixed rail 1^a. When the switch is reversed, however, the movable rail 2^a

then engages the fixed rail 1^a, and the movable rail 2 is spaced from the fixed rail 1.

Associated with the switch A is a switch operating mechanism B comprising a casing 11 which is bolted or spiked to the ties 4 adjacent the outer side of the rail 1, and an auxiliary casing 12 which is bolted to the left-hand end of the casing 11. The main casing 11 is provided with a removable cover 13, while the auxiliary casing 12 is provided with a removable cover 14.

Extending downwardly through the main casing 11 is a rotatable spindle or switch actuating shaft 16, and attached to the lower end of this shaft is an adjustable crank 17 which is pivotally connected with the previously described operating rod 9, the parts being so proportioned that rotation of the shaft 16 through an angle of approximately 90° will move the switch between its normal and reverse positions. The lower portion of the shaft 16, that is, the portion within the casing 11 is made round, and is journaled in a bearing 18 provided in the bottom of the casing 11, and in a star block 19, which, in turn, is journaled in a bearing 20 formed in the top of the casing 11. The portion of the shaft 16 above the top of this star block bearing, however, is made square, and has a somewhat smaller cross-sectional area than the lower portion of the shaft. Secured to the square portion of the shaft is a square sleeve 21, and slidably mounted on this sleeve is an outer sleeve 22 which is provided with a square opening to receive the inner sleeve so that both sleeves and the shaft are constrained to rotate together.

When the outer sleeve 22 occupies its lowermost position on the inner sleeve, in which position it is shown in the drawings, a squared portion 23 formed on the lower end of the outer sleeve enters a square recess or socket 24 formed in the upper end of the star block 19, and, under these conditions, the outer sleeve, and hence the shaft 16, is connected with the star block, so that any rotation of the shaft will cause corresponding rotation of the star block. When, however, the outer sleeve 22 is moved to an upper position on the inner sleeve, the square portion 23 on the lower end of the outer sleeve becomes disengaged from the socket 24 in the star block, and the two sleeves and the shaft are then free to rotate as a unit independently of the star block.

The outer sleeve 22 is arranged to be moved between its two extreme positions by means of a hand lever 27 which also serves as a means for rotating the switch actuating shaft between its two extreme positions. This lever is bifur-

55

cated at one end, and the bifurcations thereof are disposed on opposite sides of the squared portion formed at the upper end of the outer sleeve and are pivoted on their free ends on a bolt 28 mounted in a lug 29 formed on the inner sleeve 21. Each bifurcation extends between a pair of lugs 30 which are secured to the associated side of the outer sleeve 22, only one pair of lugs being visible in the drawings. 5 The parts are so proportioned that when the lever 27 is rotated about the bolt 28 to the depending position in which it is shown in the drawings, the outer sleeve 22 will be moved to its lowermost position on the inner sleeve, but 10 that, when the lever 27 is rotated about the bolt 28 to a substantially horizontal position the outer sleeve will then be moved to its upper position on the inner sleeve. It follows that the switch actuating shaft 16 will be connected with, 15 or disconnected from, the star block 19 according as the lever 27 occupies its depending or its horizontal position, and that, when the lever occupies its horizontal position, the shaft 16 may be rotated between its two extreme positions to 20 move the switch points to their corresponding extreme positions by rotating the lever about the axis of the shaft without causing rotation of the star block.

When the hand lever 27 occupies its depending position, which position is its normal position, it may be locked in this position by placing a padlock or other suitable locking device through a hole 151^a formed in the outer end of a lug 151 which is fastened to the outer sleeve 22, and which passes through a suitable slot 152 of the lever 27.

A suitable signal, here shown as a pair of vanes 31, positioned 90° with respect to each other in plan view, is fastened to the upper end of the switch actuating shaft 16 and serves to accurately indicate at all times the position of the switch.

The star block 19 is normally biased to the position in which it is shown in the drawings by means of two spring units S¹ and S² which are 45 located in the left-hand end of the main casing 11. These spring units are similar and a description of one will therefore suffice for both. Referring particularly to the spring unit S¹ shown in detail in Fig. 4, this spring unit comprises a cylindrical housing 32 having an end plate 33 provided with vertically spaced apertured lugs 34 and an end plate 35 provided with a centrally disposed hole 35^a. Located within the housing 32 is a coil spring 37, one end of which 50 abuts against an outwardly extending flange 38^a forming part of a member 38, and the other end of which abuts against an outwardly extending flange 39^a forming part of a member 39. The member 38 is free to slide in an axial direction 55 within the housing 32, and is provided at the end opposite to the flange 38^a with an inwardly extending annular flange 38^b which forms a centrally located hole 38^c. The member 39 is likewise free to slide in an axial direction within the 60 housing 32, and is provided with a centrally located hole 39^b. A tube 40 is screwed onto the inner end of the member 38, and mounted within this tube between the member 38 and an end plate 41 which is screwed into the right-hand 65 end of the tube is a compressed coil spring 42. A hole 41^a is formed in the end plate 41 in axial alignment with the hole 38^c in the member 38, and slidably mounted in the tube 40 between the spring 42 and the end plate 41 is a washer 43 70 having a centrally located hole 43^a, the diameter

of which is somewhat smaller than the diameter of the hole 41^a in the end plate 41. A spring bolt 44 passes through the hole 35^a in the end plate 35, the hole 39^b in the member 39, the hole 41^a in the end plate 41, the hole 43^a in the washer 43, and the hole 38^c in the member 38, and is provided at its inner end with a head 44^a which cooperates with the left-hand side of the inwardly extending flange 38^b of the member 38. Threaded on the outer end of the spring bolt 44 10 is a nut 45 and an eye 46, and slidably mounted on the spring bolt adjacent the nut 45 is a sleeve 48 which extends with clearance through the hole 39^b in the member 39 and cooperates at 15 its inner end with the washer 43 in such manner that, if the spring bolt is moved into the housing more than a predetermined distance, the sleeve will engage the washer 43 and compress the spring 42, the hole 41^a in the end plate 41 being made sufficiently large to permit the sleeve 20 48 to freely enter this hole. A shoulder 48^a having a diameter which is somewhat smaller than the diameter of the hole 35^a in the end plate 35, but which is somewhat larger than the diameter of the hole 39^b in the member 39, is 25 formed on the outer end of the sleeve 48, and the nut 45 is screwed to such a position on the bolt that when the members 38 and 39 are each 30 engaging the associated end plate, the head 44^a of the bolt 44 will engage the flange 38^b of the member 38 and the shoulder 48^a on the sleeve 48 will engage the outer face of the member 39. It will be seen, therefore, that movement of the 35 spring bolt 44 relative to the housing 32 in either direction will act through the member 38 or the member 39, as the case may be, to compress the outer spring 37, but that the inner spring 42 will only become compressed in the event that the bolt 44 is moved into the housing 32 beyond the position in which the inner end of the sleeve 40 48 moves into engagement with the washer 43. The eye 46 is locked in place on the outer end of the spring bolt 44 by means of a cotter key 47.

The right-hand end of the spring unit S¹ is 45 operatively connected with the star block 19 by means of a pin 50 which passes through the associated eye 46 and through a pair of vertically spaced lugs 51 which are formed integrally with the star block and which straddle the eye; and the right-hand end of the spring unit S² is 50 similarly operatively connected with the star block 19 by means of a pin 52 which passes through the eye 46 of this latter spring unit and through a pair of vertically spaced lugs 53, which are also formed integrally with the star block, 55 and which straddle the last-mentioned eye. The two pairs of lugs are angularly spaced from each other by a distance of approximately 100°, as shown in Fig. 3, and are also vertically spaced from each other a sufficient distance to permit 60 the unit S² to swing underneath the unit S¹ under certain conditions which will appear hereinafter.

The left-hand ends of the two spring units S¹ and S² are operatively connected with a floating 65 supporting plate 54 (see Fig. 5) at its opposite sides, and in vertically spaced relation, by means of pins 55 and 56 which pass through the lugs 34 on the end plates 33, and through cooperating lugs 57 and 58 formed on the supporting plate. 70 The supporting plate 54 is slidably mounted on the square shanks of bolts 59 and 60 in such manner that the plate is free to swing about a vertical axis which coincides with the axis of the pin 55, or a vertical axis which coincides with 75

the axis of the pin 56. The bolts 59 and 60 are secured to the end wall of the housing 11 and are provided with rectangular heads which, on the sides adjacent the shanks are beveled in the manner shown, and act as stops to limit the motion of the plate 54 toward the star block under some conditions. Movement of the floating plate 54 in the opposite direction is limited by rounded stops 61 and 62 which cooperate with stop surfaces 63 and 64, respectively, formed on the end wall of the casing 11. The parts are so proportioned that when the star block 19 occupies the position shown, and the floating plate 54 occupies the position in which the stops 61 and 62 engage the associated stop surfaces 63 and 64, both spring units S¹ and S² will exert a force on the star block which is sufficient to hold the star block in the position shown when the star block is connected with the switch, but which is not sufficient to compress the springs 37 of the spring units S¹ and S² beyond their initial compression.

The floating plate 54 is pivotally connected at its center by means of a pivot pin 65 with one end of a pull rod 66, the other end of which is secured to a substantially rectangular yoke 67 that surrounds the star block 19. The yoke 67 is slidably supported on a cam 68 which is formed integral with the star block, and has secured thereto three rollers 70, 71, and 72. The rollers 70 and 71 are disposed at opposite sides of the yoke, and cooperate with the opposite edges of a cam 73, which is also formed integrally with the star block, to position the yoke in a transverse direction with respect to the star block when the star block occupies the position shown. The roller 72 cooperates with the cam 73 in such manner that rotation of the star block in either direction from the position shown will move the yoke, and hence the pull rod 66, toward the right.

The right-hand side of the yoke 67, as viewed in Figs. 2 and 3, is provided with a tail piece 74 which carries a guide roller 75 and a latch block 76 having beveled sides. The guide roller 75 cooperates with one end 77^a of a transversely extending groove 77 provided in the underside of a latch arm 78 forming part of an electric latch E, and the latch block 76 cooperates with the other end 77^b of the groove 77. The latch arm 78 is mounted at one end on a pivot pin 79 secured to the casing 11, and carries at its opposite end an armature 78^a which cooperates with an electromagnet 80. The electromagnet 80 is secured to the casing 12, and is connected in a track circuit which includes the two stock rails 1 and 1^a in parallel (see Fig. 1) and a source of current, here shown as a battery F. It will be seen, therefore, that the electromagnet 80 will become energized whenever a train trails the switch. The end 77^a of the groove 77 is formed with vertical sides, while the other end 77^b is formed with beveled sides which slope downwardly and outwardly, as shown by Fig. 7.

The apparatus also includes two rocker arms 85 and 86. The rocker arm 85 is pivotally supported intermediate its ends on a pivot pin 87 mounted in a pair of spaced lugs 91 secured to the sides of the casing 11, and is provided at one end with a roller 88 which cooperates with the edge 68^a of the cam 68. The other end of the rocker arm 85 cooperates with a roller 89 (see Fig. 5) mounted on the upper end of the pin 56 which secures the spring unit S² to the floating plate 54. The rocker arm 86 is similar to the rocker arm 85 except that it is of the opposite hand, and this latter rocker arm is pivotally sup-

ported intermediate its ends on a pivot pin 90 mounted in a pair of spaced lugs 92 secured to the side of the casing 11 directly opposite the lugs 91. The rocker arm 86 is provided at one end with a roller 93 which cooperates with the edge 68^a of the cam 68, and the free end of this rocker arm cooperates with a roller 94 (see Fig. 5) mounted on the lower end of the pin 55 which secures the spring unit S¹ to the floating supporting plate 54. A spring 95 is stretched between the two rocker arms, and constantly biases these arms to the position in which the rollers 88 and 93 engage the cam 68. The parts are so proportioned that when the star block occupies its normal position in which it is shown in the drawings, and the rollers 88 and 93 are engaging the cam 68, the ends of the rocker arms will cooperate with the rollers 89 and 94 to hold the floating plate 54 in the position shown, but that, when the star block is rotated away from the position shown in a counterclockwise direction, as viewed in Fig. 3, the roller 88 will ride up onto the high part of the cam 68, and will thus rotate the rocker arm 85 in a counterclockwise direction to the position shown in Fig. 9 in which position the roller 89 of the floating plate 54 is free to move past the end of the rocker arm, and that, when the star block is rotated away from the position shown in a clockwise direction, as viewed in Fig. 3, the roller 93 will ride up onto the high portion of the cam 68, and will thus rotate the rocker arm 86 in a clockwise direction, as viewed in Fig. 3, to the position in which the roller 94 on the floating plate 54 is free to move past the end of the rocker arm 86.

Reciprocably mounted in the bottom of the casing 11 is a locking device 100 (see Fig. 8) which in the particular embodiment of my invention here illustrated, comprises two spaced end members 100^a and 100^b connected together by means of a pair of spaced bolt members 100^c and 100^d. The right-hand end member 100^a is provided on its right-hand side with an integral rectangular locking plunger 100^e, while the left-hand end member 100^b is provided with a centrally located hole 100^f. The locking plunger 100^e is mounted to slide in a guideway 101 (see Fig. 2) formed in the bottom of the casing 11, and is adapted to cooperate with a lock rod L which is slidably mounted in the casing 11 at right angles to the locking plunger. The lock rod L is of standard construction, and comprises two longitudinally adjustable bars 103^a and 103^b (see Fig. 1) attached at one end to the front rod 5 of the switch A, and provided with two registering notches 103^c so disposed that these notches will align with the locking plunger when and only when the switch A occupies its normal extreme position in which it is shown in the drawings. The locking device 100 is arranged to be moved, in a manner which will be described hereinafter, between a right-hand extreme position in which the locking plunger 100^e is within the notches 103^c in the rod L, and a left-hand extreme position in which the locking plunger 100^e is withdrawn from the notches 103^c, and it will be apparent that when the locking device is moved to the position in which the locking plunger is within the notches, the switch A will be positively locked in its normal extreme position, but that, when the locking device is moved to the position in which the locking plunger is withdrawn from the notches 103^c in the lock rod L, the switch A will then be unlocked.

The bolt members 100^c and 100^d of the locking device 100 are slidably mounted adjacent their

left-hand ends in suitable guides 106 and 107, respectively, which are provided on the bottom of the main casing 11, and surrounding each bolt member between the end member 100^a and the associated guides 106 and 107 is a tightly compressed coil spring 108 which constantly biases the locking device 100 to its right-hand extreme position.

A bell crank lever 109 is pivoted on a rod 110 mounted in a pair of spaced plugs 111 which are screwed into the sides of the casing 11 and the one arm 109^a thereof extends downwardly and is provided at its lower end with a rounded portion 109^b which cooperates with an L shaped extension 100^b provided on end member 100^a, in a manner which will be described hereinafter. The other arm 109^c of the bell crank lever 109 extends toward the left as viewed in Fig. 2, and is pivotally connected at its free end by means of a pin 112 with the lower end of a vertically extending connecting rod 114.

The connecting rod 114 is shaped as shown, and comprises an integral offset portion 114^a. This connecting rod extends upwardly through arcuate slots 115 and 116 formed in the cams 68 and 73, and through a guideway 117 formed in the top wall of the casing 11, and is provided at its upper end with a lateral extension 114^b which overlies and cooperates with an annular flange 118 formed on the sliding sleeve 22 directly above the squared portion 23. A two-piece collar 119 is bolted to the sliding sleeve 22 some distance from the annular flange 118 and lateral extension 114^b, and extending downwardly from this collar is a frusto-conical hood 120 which completely encloses the upper part of the offset portion 114^a of the connecting rod 114 and the annular flange 118, thus protecting these parts from dirt, moisture, etc.

The connecting rod 114 is also provided with an integral lateral extension 114^c which overlies and cooperates with cam faces 73^a and 73^b formed on the upper side of the cam 73. The two cam faces 73^a and 73^b curve downwardly toward each other, as shown in Figs. 2 and 6.

The parts are so proportioned that when the sliding sleeve 22 occupies its lowermost position, and the star block 19 occupies the position to which it is biased by the spring units S¹ and S², as shown in the drawings, the connecting rod 114 will be moved to the position in which it is shown in the drawings, which position I shall herein-after refer to as its "lowermost" position. The parts are further so proportioned that when the connecting rod 114 occupies its lowermost position, the underside of the lateral extension 114^b of the connecting rod will engage the upper side of the annular flange 118, the underside of the lateral extension 114^c will engage the cam 73 between the two cam faces 73^a and 73^b, and the bell crank lever 109 will be rotated to a position in which the rounded portion 109^b would engage the left-hand side of the end member 100^a of the locking device 100 if the locking device were then moved to its extreme right-hand position by the biasing springs 108.

The locking device 100, in addition to being operatively connected with the sliding sleeve 22 and the star block 19 in the manner just described, is also operatively connected with the previously described tie rod 8 by means of linkage which I will now describe.

As here shown, this linkage includes a plunger bolt 121 (see Figs. 1, 2, and 3) which extends with some clearance through the hole 100^c in the

end member 100^b of the locking device 100, and the head of which bolt cooperates with the right-hand side of the end member 100^b. The threaded left-hand end of the plunger bolt 121 is adjustably connected by means of a turnbuckle 122 with one end of a link 123, the other end of which link is pivotally connected with a long arm 124^a and a bell crang lever 124. The bell crank lever 124 is pivotally supported in a crank stand 125, and has its short arm 124^b pivotally connected with one end of an operating rod 126. The other end of the operating rod 126 is connected by means of a standard switch basket 127 with the previously described tie rod 8. The tie rod 8 may be located at any desired location, but will preferably be located approximately half-way between the heel and the point of the switch. The base 128 of the crank stand 125 is secured both to a gauge plate 129, and to the bed plate 15, which bed plate, in turn, is secured to the mechanism B, and it will be apparent, therefore, that any loss of adjustment between the parts due to creepage of the ties is prevented.

For reasons which will be made clear presently, the extreme position to which the locking plunger 100^e is movable within the notches 103^c in the lock rod L is beyond the normal locking position in which it is shown in the drawings, and the linkage connecting the locking device with the tie rod 8 is so adjusted that when the switch occupies its normal extreme position the head of the plunger bolt 121 will engage the end member 100^b when the locking plunger has been moved to its locking position and will prevent the locking plunger from moving beyond its locking position.

The auxiliary casing 12 referred to hereinbefore houses a circuit controller C in such manner that this circuit controller can be added to or removed from the remainder of the switch operating apparatus without disturbing the remainder of the switch operating apparatus. The details of construction of this circuit controller are similar in all respects to those of the circuit controller described and claimed in Letters Patent of the United States No. 1,989,128, granted to me on January 29, 1935, for Railway switch circuit controllers, and in themselves form no part of my present invention, except insofar as they are used in combination with the rest of the apparatus. Briefly, this circuit controller includes two separate sets of contacts, one set of which is usually referred to as plunger lock contacts and the other set of which is usually referred to as point detector contacts. The plunger lock contacts are each designated by the reference characters 130—131, and are all controlled by a contact operating member 132 pivotally attached to one end of a rocker arm 133, which rocker arm, in turn, is pivoted intermediate its ends on a fixed pin 134, and is provided in the end opposite to the operating member with a cam slot 135, and with a cam face 135^a which cooperates with a roller 136 mounted in the upper end of a bracket 137 secured to the upper face of the locking plunger 100^e. When the locking device 100 occupies its locking position in which position it is shown in the drawings, the roller 136 engages the cam slot 135 at an offset portion 135^b, and under these conditions, the rocker arm 133 is rotated to an extreme position in which the plunger lock contacts 130—131 are all closed. When, however, the locking device 100 is moved in either direction from its normal locking position, the roller 136 is forced out of the offset portion 135^b of the cam slot 135, and the rocker arm 133 is then rotated to another extreme posi-

tion. The roller 136 is forced out of the offset portion 135^b of the cam slot 135, and the rocker arm 133 is then rotated to another extreme posi-

tion in which the plunger lock contacts 130—131 are open.

The point detector contacts of the circuit controller C are each designated by the reference characters 138—139, and are all controlled by a contact operating member 140 provided with a roller 141 which cooperates with a recess 142 formed in the point detector rod D. The point detector rod D is slidably mounted in the casing 12 transversely thereof, and is attached at one end by means of a link 104^a and a bolt member 104^b to the movable rail 2 of the switch A in the usual and well-known manner. The recess 142 in the point detector rod D is so positioned that it will align with the roller 141 when and only when the switch occupies its normal position and the movable rail 2 is tight against the fixed rail 1, and the parts are so proportioned that when the recess 142 aligns with the roller 141, this roller will enter the notch, thereby permitting the contact operating member 140 to rotate by gravity to a position in which it is out of engagement with the contact fingers 138 of the point detector contacts, thus causing these contacts to close by virtue of the inherent resiliency of the contact fingers. When, however, the roller 141 is forced out of the recess 142 in the point detector rod D, the contact operating member 140 will be positively rotated to the position in which the point detector contacts 138—139 become opened.

The circuit controller C further comprises lock mechanism whereby, if the roller 141 is forced out of the recess 142 in the point detector rod D, when the locking device 100 occupies any position in which the locking plunger 100^e is within the notches 103^c in the lock rod L, the point detector contacts will, after becoming opened in the manner previously described, subsequently be held open until the latch mechanism is manually operated to permit these contacts to again become closed. The plunger lock contacts and point detector contacts of circuit controller C may be used to control signals for controlling traffic over switch A in a well-known manner.

The operation of the apparatus as a whole is as follows: As shown in the drawings, the movable rails of the switch are in their normal position and the hand-throw lever 27 occupies its depending position. Under these conditions, the sliding sleeve 22 is held in its lowermost position on the inner sleeve 21, and the star block 19 is accordingly connected with the switch actuating shaft 16 so that the spring units S¹ and S² are effective to hold the movable rails of the switch in their normal positions. Furthermore, under these conditions, the connecting rod 114 is held in its lowermost position, and the locking device 100 is held in its locking position by the biasing springs 108. As was previously pointed out, when the locking device 100 occupies its locking position, the movable rails of the switch are locked in their normal position, and the plunger lock contacts 130—131 of circuit controller C are closed. Point detector rod D occupies the position in which the recess 142 aligns with the roller 141 and the point detector contacts 138—139 of circuit controller C are, therefore, closed. Since both the point detector and plunger lock contacts of circuit controller C are closed, the signals governing traffic

over switch A would display a proceed indication, thereby indicating that the movable rails of switch A are in their normal positions and are properly locked in these positions for main line traffic over the switch. The circuit for the magnet 80 of the electric latch E is open, and this magnet is there-

fore deenergized so that the latch arm 78 is free to move upwardly.

I will now assume that it is desired to reverse the switch A. To do this, the hand lever 27 is first raised to its horizontal position. This preliminary movement of the hand lever raises the sliding sleeve 22 from its lowermost position in which it is shown in the drawings to its uppermost position, and, as was previously described, when the sliding sleeve 22 is moved to its uppermost position, the squared portion 23 on the lower end of this sleeve becomes disengaged from the socket 24 in the upper end of the star block 19, thus disconnecting the star block, and hence the spring units S¹ and S², from the switch actuating shaft, so that the switch actuating shaft is then free to rotate without any opposition from the biasing devices. Furthermore, when the sliding sleeve 22 is moved to its uppermost position, the annular flange 118 on the lower end of this sleeve cooperates with the lateral extension 114^b of the connecting rod 114 to move the connecting rod 114 to its uppermost position, and this movement of the connecting rod, in turn, acts through the bell crank lever 109 to move the locking device 100 from its normal locking position in which it is shown in the drawings to a position in which the locking plunger 100^e is completely withdrawn from the notches 103^c in the lock rod L, thus unlocking the switch, and at the same time actuating rocker arm 133 of circuit controller C to open the plunger lock contacts 130—131 of the circuit controller. The biasing devices now being disconnected from the switch actuating shaft and the switch being unlocked, the hand-throw lever is next rotated in the horizontal plane which it then occupies, through an angle of approximately 90° in a counterclockwise direction. This intermediate movement of the hand lever rotates the switch actuating shaft 16 to the extreme position opposite to that in which it is shown in the drawings, thereby reversing the movable rails of the switch in the manner previously described. As soon as the movable rails start to move to their reverse positions, recess 142 in point detector rod D moves out of alignment with roller 141, thus opening the point detector contacts 138—139 of circuit controller C. Furthermore, as the movable rails move to their reverse positions, the linkage which connects the locking device 100 with the tie rod 8 is actuated in such manner that the plunger bolt 121 is moved toward the left, and as soon as the plunger bolt has moved as far as the locking device was previously moved by the bell crank lever 109, the plunger bolt will engage the end member 100^b of the locking device 100, and during the balance of the movement of the plunger bolt the locking device will be moved with the plunger bolt, so that when the switch reaches its full reverse position the locking device will be moved to its extreme left-hand position. The switch points now being fully reversed, the hand lever 27 is next restored to its depending position. The final movement of the hand lever, of course, restores the sliding sleeve 22 to its lowermost position, thus reconnecting the star block 19 with the switch actuating shaft, and at the same time permitting the connecting rod 114 to return to its lowermost position.

If, when the switch has been moved to its reverse position in the manner just described, it is desired to restore the switch to its normal position, the hand lever 27 is first raised to its horizontal position, and is then rotated in a clockwise direction through an angle of 90°, as viewed in

Fig. 1, and is finally restored to its depending position and relocked in this position. The operation of the various parts of the apparatus under these conditions is just the reverse of that described above, and will be readily understood from the foregoing, and from an inspection of the drawings, without further description.

I will now assume that the parts are in their normal positions, as shown in the drawings, and that a train trails the switch. As the leading wheels of a train roll along the fixed rail 1, the movable rails 2 and 2^a are forced over but before a sufficient force is developed at the points of these rails to overcome the opposing force of the spring units S¹ and S², and cause the point of the movable rail 2 to move out of engagement with the fixed rail 1, the movable rails being somewhat resilient, become bent so that with the usual standard split switch, the tie rod 8 will be moved upwardly, as viewed in Fig. 1, three-quarters of an inch or more. This movement of the tie rod 8 acting through the switch basket 121, operating rod 126, bell crank lever 124, link 123, and plunger bolt 121, moves the locking device 100, in opposition to the bias of the springs 108, a sufficient amount to completely withdraw the locking plunger 100^a from engagement with the notches 103 in the lock rod L, thus unlocking the switch. As a result, when the leading wheels of the train have reached the position in which a sufficient force is developed at the points of the movable rails to cause the point of the movable rail 2 to move out of engagement with the fixed rail 1, the movable rails will be unlocked, and these rails will, therefore, be forced away from their normal positions by the wheels of the train in exactly the same manner as they would be if no point lock were provided. The movement of the movable rails away from their normal positions acts through the operating rod 9 and crank 17 to rotate the shaft 16 in a counterclockwise direction, and this rotation of the shaft 16, in turn, rotates the associated sleeves 21 and 22, and the star block 19 in the same direction. The first few degrees of rotation of the star block 19 causes the high portion of cam 68 to engage roller 88 and rotate rocker arm 85 in a counterclockwise direction to the position in which the left-hand end of this rocker arm is out of alignment with the roller 89. Further rotation of the star block 19 causes cam 73 to engage roller 72 and thereby move the yoke 67 and pull rod 66 toward the right. During this movement, the rocker arm 86 remains in the position shown, so that the lower end of the floating plate 54, as viewed in Fig. 3, is prevented from moving toward the right, and as a result the movement of the pull rod 66 toward the right causes the motion plate to swing in a clockwise direction about the axis of the roller 94 as a fulcrum. The rotation of the star block also acts through the lugs 51 to move the spring bolt 44 of the spring unit S¹ toward the right, and since the motion plate 54 at the side to which the spring unit S¹ is attached is prevented from moving to the right, the spring bolt 44 acts through the member 38 to compress the spring 37, and hence causes the spring unit S¹ to exert an increased force tending to restore the movable rails to their normal positions. It will be noted that the movement of the spring bolt 44 of the spring unit S¹ which takes place under these conditions does not cause the spring 42 to become compressed, so that the entire force which is exerted by the spring unit S¹ is due to the spring 37. The rotation of the

star block 19 further acts through the lugs 53 to move the spring bolt 44 of the spring unit S² toward the left until after the switch points have been moved a short distance beyond their mid stroke positions, whereupon the spring bolt 44 of the spring unit S² is moved in the opposite direction. During this movement of the spring bolt, the housing 32 is simultaneously moved toward the right due to the previously described motion of the motion plate 54, and the parts are so proportioned that the resultant relative movement between the housing and the spring rod will always be in a direction to force the spring rod further into the housing 32. The parts are further so proportioned that shortly after the switch points have been moved past their mid stroke positions, the end of the sleeve 48 of the spring unit S² will move into engagement with the washer 43, and it will be seen, therefore, that during the movement of the switch points toward their mid stroke positions, only the spring 37 of the spring unit S² will become compressed, but that after the switch points have been moved past their mid stroke positions, the springs 37 and 42 of the spring unit S² will then both become compressed. It will also be seen that the spring unit S² and lugs 53 function like a toggle, so that while the points are being moved to their mid stroke positions, the force due to the spring unit S² will be in a direction to oppose the movement of the points, but that, as soon as the points have passed their mid stroke positions, the force due to the spring unit S² will then be in a direction to aid the movement of the points. The reaction between the cam 73 and the roller 72 also produces some force on the switch points tending to restore them to their normal positions, and results in a side thrust on the yoke 67. This side thrust, however, due to the fact that the magnet 80 is now energized by virtue of the track circuit of which it forms a part being completed by the wheels and axles of the train so that the latch arm 78 is held down, is resisted by engagement of roller 75 with the straight sides of the groove 77 in the latch arm until after the switch points have been moved to within a short distance of their full stroke positions, after which this side thrust is then resisted by engagement of the latch block 76 with the beveled side portion of the groove 77. The reason for resisting the side thrust on the yoke 67 by means of the roller 75 engaging the straight side portion of the notch during the first part of the stroke, and for resisting the side thrust by means of the latch block 76 with the beveled side portion of the notch during the latter part of the stroke, is that the side thrust is smaller at the end of the stroke than it is at the beginning, and it is desirable to keep the size of the magnet 80 as small as possible, and at the same time insure that the latch will release if the magnet becomes deenergized when the switch is in its full reverse position. With the above described construction, the only time that the magnet 80 has to resist any appreciable upward force on the latch arm is when the switch points have been moved to substantially their full stroke positions in which positions the force of the latch arm is a minimum, thus making it possible to use a magnet of minimum size. The magnitude of the various forces which are exerted on the switch points as the switch points move from their normal to their reverse positions in response to the trailing train are shown graphically in Fig. 10, and it will be apparent from an examination of this figure that

the force exerted on the points by the spring unit S^2 when the points are within a short distance of their reverse positions becomes greater than the opposing force due to spring unit S^1 and the reaction of the cam 73 against the roller 72 , with the result that the spring unit S^2 becomes effective to force the switch points to, and hold them in, their full reverse positions. The positions which the various parts of the mechanism B occupy when the switch points have been moved to their full reverse positions in response to the movement of the trailing train through the points is shown in Fig. 9. After the train has completely passed the switch, it will move off the track circuit in which the magnet 80 is included, and will thus cause this magnet to become de-energized. When this happens, the upward reaction on the latch arm 78 caused by the side thrust of the latch block 76 against the sloping sides of the groove 77 in the latch arm will cause the latch arm to swing upwardly and release the yoke 67 , whereupon the yoke 67 will immediately swing upwardly and toward the left, as viewed in Fig. 9, in such a manner as to allow the motion plate 58 to return to its normal position in which it is shown in the drawings, due to the reaction on the motion plate caused by the spring unit S^2 . The return movement of the motion plate to its normal position causes the force which is exerted on the switch points by the spring unit S^2 to decrease below that which is exerted on the points by the spring unit S^1 , and the switch points will therefore immediately start to return to their normal positions. As the switch points return to their normal positions, the resultant rotation of the star block 19 will cause the cam 73 to cooperate with the roller 70 in a manner to return the yoke 67 to its centralized position in which it is shown in Fig. 3, and when the yoke reaches this position, the latch arm 78 will immediately drop to its normal position in which it is shown in Fig. 3. The movement of the star block to its normal position will also permit the connecting rod 114 to return by gravity to its lowermost position and will cause roller 88 to move off the high portion of cam 68 and onto the low portion of the cam, thereby permitting spring 95 to restore rocker arm 85 to its normal position in which it is shown in Fig. 3. Furthermore, during the return movement of the switch points to their normal positions, the linkage which connects the locking device 100 with the tie rod 8 will permit the biasing springs 108 to return the locking device 100 toward its locking position, and since there is no deflection of the switch points under these conditions, the locking plunger 100^e will be moved into engagement with the side of the lock rod L before the movable rails of the switch points have reached their full normal position in which the lock rod is in the proper position for the notches 103^c to receive the locking plunger. As a result, after the locking plunger has once moved into engagement with the side of the lock rod, the locking plunger will slide along the side of the lock rod until the notches 103^c in the lock rod move into alignment with the locking plunger, at which time the energy stored in the compressed springs 108 will force the locking plunger to its normal locking position, thus restoring the switch to its normal locked condition. If the notches 103^c in the lock rod L should not come into alignment with the locking plunger under these conditions for any reason, or if the notches should come into alignment with the locking plunger and the linkage which connects the lock-

ing device 100 with the tie rod 8 was then out of adjustment, or was permitted to move beyond its normal locking position, plunger lock contacts $130-131$ of circuit controller C would remain open, thus causing the signals controlled by the circuit controller to remain at danger. Furthermore, if, while the train was trailing the switch, the movable point 2 should have become bent or damaged so that when the movable rails had returned to their normal conditions, the movable rail 2 failed to assume its proper position with respect to the fixed rail 1 , the point detector contacts $138-139$ of circuit controller C would remain open, which would also cause the signals controlled by circuit controller C to remain at danger. It follows, therefore, that with apparatus embodying my invention, under no conditions can a dangerous condition exist due to a train trailing the switch when the switch occupies its normal condition.

I will now assume that the switch A has been moved to its reverse position by means of the switch operating mechanism E in the manner previously described and that a train trails the switch. Under these conditions, as the leading wheels of the train roll along the fixed rail 1^a and movable switch point 2 , the movable rails will become deflected in much the same manner as when the switch occupies its normal position and a train trails the switch, but this deflection will now be in the opposite direction so that the plunger bolt 121 of the linkage which connects the locking device 100 with the tie rod 8 will move toward the right instead of toward the left. As a result, the locking device which, it will be remembered, normally occupies its extreme left-hand position when the switch occupies its reverse position and no train is trailing the switch, will now be moved toward its locking position by the biasing springs 108 a certain amount, which amount may be sufficient to allow the locking plunger 100^e to move into engagement with the side of the lock rod L . This movement of the locking device, however, will not cause the locking plunger to enter the notches 103^c in the lock rod L because when this movement takes place, the notches 103^c in the lock rod will then be out of alignment with the locking plunger. As the movable rails are forced open, shaft 16 , sleeves 21 and 22 , and star block 19 are rotated toward the position corresponding to the normal position of the switch, and lock rod L is likewise moved toward the position corresponding to the normal position of the switch. The rotation of the star block 19 actuates the two spring units S^1 and S^2 in such manner that the unit S^1 now becomes effective to bias the movable rails to their normal positions in substantially the same manner that the spring unit S^2 became effective to bias the movable rails to their reverse positions when the switch points were trailed toward these positions from their normal positions, and the magnet 80 becomes effective to resist the side thrust on the yoke 67 as long as the train continues to trail the switch. Furthermore, the rotation of the star block 19 causes the cam face 73^b of the cam 73 to force the connecting rod 114 upwardly in the same manner as when the switch was trailed in the normal position. As a result of this upward movement of the connecting rod, bell crank lever 109 is rotated in a clockwise direction to such a position that it engages the extension 100^h of the end member 100^a of the locking device 100 , and thereby moves the locking device to a

position in which the locking plunger 100^e is out of engagement with the side of the lock rod L. It will be seen, therefore, that under these conditions, even though the switch is forced to its full normal position by the trailing train, thus causing the notches 103^e in the lock rod L to move into alignment with the locking plunger, the locking plunger cannot move to its locking position. It follows that with apparatus embodying my invention it is impossible for the switch to become locked in its normal position if it is moved to its normal position from its reverse position by a trailing train. After the train has completely trailed the switch, the magnet 80 will become deenergized and will allow the latch arm 78 to move upwardly in substantially the same manner as when the switch is trailed from its normal position. When this happens, the floating plate 54 will return to its normal position and will thus cause the biasing force exerted on the switch points by the spring unit S¹ to become less than that exerted on the points by the spring unit S² with the result that the switch points will then immediately start to return to their normal positions. As the switch points return to their normal positions, the cam 73 will cooperate with the roller 71 to return the yoke 67 to the position shown, and the roller 93 will ride off the high portion of cam 68 onto the low portion of this cam, and will thus permit the rocker arm 86 to return to the position in which it is shown in the drawings. As soon as the yoke 67 reaches its normal position, the latch arm 78 will return by gravity to its normal position. Furthermore, as the star block 19 returns to its normal position, connecting rod 114 will also return by gravity to its lowermost position. Locking plunger 100^e, however, will remain out of engagement with lock rod L because as the switch points return to their reverse positions, there will be no deflection of the movable rails, and the resultant operation of the linkage which connects the locking device with the tie rod 8 will restore the locking device to its extreme left-hand position. When the movable switch points have reached their full reverse positions, all parts will then occupy the same positions which they occupied before the train started to trail the switch.

One advantage of apparatus embodying my invention is that it combines within one mechanism means for throwing the switch between its two extreme positions, a mechanically operated facing point lock which locks the switch for facing point moves but becomes automatically unlocked for a trailing move, spring means for permitting the switch to be trailed, spring means for forcing the switch points to their full trailed positions when a train trails the switch and for subsequently holding the points in their full trailed positions until after the train has completely passed the switch, and latching means for releasing the spring mechanism and allowing the switch to return to its original position after a train which is trailing the switch has completely passed the switch.

Although I have herein shown and described only one form of railway switch operating apparatus embodying my invention, it is understood that various changes and modifications may be made therein within the scope of the appended claims without departing from the spirit and scope of my invention.

Having thus described my invention, what I claim is:

1. In combination, a switch actuating shaft, a star block, means for connecting said star block with and disconnecting it from said shaft, an electromagnetic latch, biasing means, and means controlled in part by said latch for connecting said biasing means with said star block in such manner that said biasing means is effective when said latch is deenergized to bias said star block to one position but becomes effective if said star block is rotated away from said one position more than a predetermined distance when said latch is energized for biasing said star block to another position. 5

2. In combination, a switch actuating shaft, a star block, means for connecting said star block with and disconnecting it from said shaft, an electromagnetic latch, biasing means, and means controlled in part by said latch for connecting said biasing means with said star block in such manner that said biasing means is effective when said latch is deenergized to bias said star block to one position but becomes effective if said star block is rotated away from said one position more than a predetermined distance when said latch is energized for subsequently biasing said star block to another position as long as said latch remains energized. 15

3. In combination, a switch actuating shaft, a star block, means for connecting said star block with and disconnecting it from said shaft, an electromagnetic latch, and biasing means connected with said star block and with said latch and effective when said latch is deenergized to bias said star block to one position but effective if said star block is rotated away from said one 30 position more than a predetermined distance when said latch is energized for biasing said star block to another position until said latch subsequently becomes deenergized, whereupon said biasing means again becomes effective to bias 35 said star block to said one position. 40

4. In combination, a switch actuating shaft, a star block, means for connecting said star block with and disconnecting it from said shaft, an electromagnetic latch, biasing means, and means controlled by said latch and by cam means formed on said star block for operatively connecting said biasing means with said star block in such manner that said biasing means is normally effective to bias said star block to a first 50 position but that if said star block is rotated away from said first position more than a predetermined distance when said latch is energized said biasing means will then become effective to bias said star block to a second position. 55

5. In combination, a switch actuating shaft, a star block, means for connecting said star block with and disconnecting it from said shaft, two spring units each operatively connected at one end with lugs formed on said star block, an electromagnetic latch, means for operatively connecting the other ends of said spring units with said star block and with said latch in such manner that both said spring units are normally effective to bias said star block to a first position but that if said star block is rotated away from said first position more than a predetermined distance the one unit will exert an increased force on said star block tending to restore it to said first position and the other unit will exert a force on said star block which tends to move it to a second position and which exceeds or is less than the force due to said one unit according as said latch is then energized or deenergized. 60

6. In combination, a switch actuating shaft, a 70

star block, means for connecting said star block with and disconnecting it from said shaft, two spring units each operatively connected at one end with lugs formed on said star block, means including a cam on said star block and a frame surrounding said star block and carrying rollers which cooperate with said cam for operatively connecting the other ends of said spring units with said star block, an electromagnetic latch effective when energized for controlling the movement of said frame by said cam, the parts being so arranged and so proportioned that both said spring units are normally effective to bias said star block to a first position but that if said star block is rotated away from said first position more than a predetermined distance the one unit will exert an increased force on said star block tending to restore it to said first position and the other unit will exert a force on said star block which tends to move it to a second position and which exceeds or is less than the force due to said one unit according as said latch is then energized or deenergized.

7. In combination, a switch actuating shaft, a star block, means for connecting said star block with and disconnecting it from said shaft, two spring units each operatively connected at one end with lugs formed on said star block, an electromagnetic latch, means for operatively connecting the other ends of said spring units with said star block and with said latch in such manner that both said spring units are normally effective to bias said star block to a first position but that if said star block is rotated away from said first position in one direction more than a predetermined distance the one unit will exert an increased force on said star block tending to restore it to said first position and the other unit will exert a force on said star block which tends to move it to a second position and which exceeds or is less than the force due to said one unit according as said latch is then energized or deenergized and that if said star block is rotated away from said one position in the other direction more than a predetermined distance said other unit will exert an increased force on said star block tending to restore it to said one position and said one unit will exert a force on said star block which opposes the force due to said other unit and which exceeds or is less than the force due to said other unit according as said latch is then energized or deenergized.

8. In combination, a switch actuating shaft, a star block, means for connecting said star block with and disconnecting it from said shaft, two spring units each operatively connected at one end with lugs formed on said star block, an electromagnetic latch, means including a cam on said star block and a frame surrounding said star block and carrying rollers which cooperate with said cam and a tail piece which cooperates with said latch for operatively connecting the other ends of said spring units with said star block in such manner that both said spring units are normally effective to bias said star block to a first position but that if said star block is rotated away from said first position more than a predetermined distance the one unit will exert an increased force on said star block tending to restore it to said first position and the other unit will exert a force on said star block which tends to move it to a second position and which exceeds or is less than the force due to said one unit according as said latch is then energized or deenergized and that if said star block is rotated

away from said one position in the other direction more than a predetermined distance said other unit will exert an increased force on said star block tending to restore it to said one position and said one unit will exert a force on said star block which opposes the force due to said other unit and which exceeds or is less than the force due to said other unit according as said latch is then energized or deenergized.

9. In combination, a switch actuating shaft, a star block, means for connecting said star block with and disconnecting it from said switch actuating shaft, an electromagnetic latch, a cam on said star block, a frame surrounding said star block and provided with two rollers which cooperate with said cam to move said frame to a first position with respect to said star block when said star block is rotated to a first position but for permitting said frame to be moved from its first position to a second position when said star block is rotated away from its first position in one direction and for permitting said frame to be moved away from its first position to a third position when said star block is rotated away from its one position in another direction, means on said frame cooperating with said latch and effective when said latch is energized for preventing said frame from moving to its second and third positions but for permitting said frame to move to a fourth position, a third roller on said frame cooperating with said cam to move said frame to its fourth position if said star block is rotated away from its one position in either direction when said magnet is energized, and spring means operatively connected with said star block and said frame and effective for biasing said star block to its one position when said frame occupies its first, second, or third position and for biasing said star block to one extreme position when said frame is moved to its fourth position by rotation of said star block from its first position in one direction and to another extreme position when said frame is moved to its fourth position by rotation of said star block from its first position in the other direction.

10. In combination with a railway switch, a switch actuating shaft movable between two extreme positions and operatively connected with the switch for moving the switch between its normal and reverse positions, a star block rotatable about said shaft, a manually operable lever rotatable in two planes, means responsive to rotation of said lever in one of said planes for rotating said switch actuating shaft between its two extreme positions, means responsive to rotation of said lever in the other plane for connecting said star block with and disconnecting it from said switch actuating shaft, an electromagnetic latch, means for energizing said latch whenever a train trails said switch, and biasing means connected with said star block and with said latch in such manner that said biasing means is normally effective to bias said star block to a first position but that if said star block is rotated away from said first position when said latch is energized said biasing means will then become effective to bias said star block to a second position until said latch subsequently becomes deenergized, the parts being so arranged that when said shaft is connected with said star block and said star block occupies its first position said switch will be biased to its normal or its reverse position depending upon the position which the switch occupied when it became connected with said star block.

11. In combination with a switch, means including a switch actuating shaft for moving the switch between its two extreme positions, a star block rotatable about said shaft, manually operable means for rotating said shaft between its two extreme positions independently of said star block and for connecting said star block with said shaft whenever said shaft occupies either extreme position, an electromagnetic latch, means for energizing said latch when a train trails said switch, and biasing means connected with said star block and with said latch and normally effective to bias said switch to the extreme position which it occupies when it becomes connected with said shaft but effective when a train trails the switch for biasing the switch to its opposite extreme position as long as said latch remains energized.

12. In combination with a railway switch, a switch actuating shaft movable between two extreme positions and operatively connected with the switch for moving the switch between its normal and reverse positions, a star block rotatable about said shaft, a manually operable lever rotatable in two planes, means responsive to rotation of said lever in one of said planes for rotating said switch actuating shaft between its two extreme positions, means responsive to rotation of said lever in the other plane for connecting said star block with and disconnecting it from said switch actuating shaft, an electromagnetic latch, biasing means, and means controlled by said latch and by cam means formed on said star block for operatively connecting said biasing means with said star block in such manner that said biasing means is normally effective to bias said star block to a first position but that if said star block is rotated away from said first position when said latch is energized said biasing means will then become effective to bias said star block to a second position until said latch subsequently becomes deenergized, the parts being so arranged that when said shaft is connected with said star block and said star block occupies said first position said switch will be biased to its normal or its reverse position depending upon the position which the switch occupied when it became connected with said star block.

13. In combination with a railway switch, a switch actuating shaft movable between two extreme positions and operatively connected with the switch for moving the switch between its normal and reverse positions, a star block rotatable about said shaft, a manually operable lever rotatable in two planes, means responsive to rotation of said lever in one of said planes for rotating said switch actuating shaft between its two extreme positions, means responsive to rotation of said lever in the other plane for connecting said star block with and disconnecting it from said switch actuating shaft, two spring units each operatively connected at one end with lugs formed on said star block, an electromagnetic latch, means controlled in part by said latch for operatively connecting the other ends of said spring units with said star block in such manner that both said spring units are normally effective to bias said star block to a first position but that if said star block is rotated away from said first position more than a predetermined distance the one unit will exert an increased force on said star block tending to restore it to said first position and the other unit will exert a force on said star block which tends to move it to a second position and which exceeds or is less than the force due to said one unit according as said latch

is then energized or deenergized, the parts being so arranged that when said shaft is connected with said star block and said star block occupies said first position said switch will be biased to its normal or its reverse position depending upon the position which the switch occupied when it became connected with said star block.

14. In combination with a railway switch, a switch actuating shaft movable between two extreme positions and operatively connected with the switch for moving the switch between its normal and reverse positions, a star block rotatable about said shaft, a manually operable lever rotatable in two planes, means responsive to rotation of said lever in one of said planes for rotating said switch actuating shaft between its two extreme positions, means responsive to rotation of said lever in the other plane for connecting said star block with and disconnecting it from said switch actuating shaft, an electromagnetic latch, means for energizing said latch whenever a train trails said switch, biasing means connected with said star block by means controlled in part by said latch in such manner that said biasing means is normally effective to bias said star block to a first position but that if said star block is rotated away from said first position when said latch is energized said biasing means will then become effective to bias said star block to a second position until said latch subsequently becomes deenergized, the parts being so arranged that when said shaft is connected with said star block and said star block occupies said first position said switch will be biased to its normal or its reverse position depending upon the position which the switch occupied when it became connected with said star block, means for locking the switch in its normal position constantly biased to a locking position, means for actuating said locking means from its locking position to an unlocking position prior to movement of the switch from its normal position to its reverse position by said switch actuating shaft, means actuated by a train approaching the switch in a trailing direction when said locking means occupies its locking position for actuating said locking means to an unlocking position until after the train has trailed the switch, and means controlled by said star block for preventing said locking means from moving to its locking position if said switch is moved to its normal position from its reverse position by a trailing train.

15. In combination with a switch, means including a switch actuating shaft for moving the switch between its two extreme positions, a star block rotatable about said shaft, manually operable means for rotating said shaft between its two extreme positions independently of said star block and for connecting said star block with and disconnecting it from said shaft whenever said shaft occupies either extreme position, an electromagnetic latch, means for energizing said latch whenever a train trails said switch, biasing means connected with said star block by means controlled in part by said latch and normally effective to bias said switch to the extreme position which it occupies when it becomes connected with said shaft but effective when a train trails the switch for biasing the switch to its opposite extreme position as long as said latch remains energized, locking mechanism for locking the switch in one extreme position constantly biased to a locking position, and means controlled by said star block for preventing said locking mechanism from moving to its locking position in the

event the switch is moved to said one extreme position from its other extreme position by a train trailing the switch.

16. In combination with a switch, means including a switch actuating shaft for moving the switch between its two extreme positions, a star block rotatable about said shaft, manually operable means for rotating said shaft between its two extreme positions independently of said star block and for connecting said star block with said shaft whenever said shaft occupies either extreme position, an electromagnetic latch, means for energizing said latch whenever a train trails said switch, biasing means connected with said star block by means controlled in part by said latch and normally effective to bias said switch to the extreme position which it occupies when it becomes connected with said shaft but effective when a train trails the switch for biasing the switch to its opposite extreme position as long as said latch remains energized, locking mechanism for locking the switch in one extreme position constantly biased to a locking position, means for operating said locking mechanism from its locking position to its unlocking position prior to movement of said switch from its one extreme position to its other extreme position by said manually operable means, and means controlled by said star block for preventing said locking mechanism from moving to its locking position in the event the switch is moved to said one extreme position from its other extreme position by a train trailing the switch.

17. In combination with a switch, means including a switch actuating shaft for moving the switch between its two extreme positions, a star block rotatable about said shaft, manually operable means for rotating said shaft between its two extreme positions independently of said star block and for connecting said star block with said shaft whenever said shaft occupies either extreme position, an electromagnetic latch, means for energizing said latch whenever a train trails said switch, biasing means connected with said star block by means controlled in part by said latch and normally effective to bias said switch to the extreme position which it occupies when it becomes connected with said shaft but effective when a train trails the switch for biasing the switch to its opposite extreme position as long as said latch remains energized, locking mechanism for locking the switch in one extreme position constantly biased to a locking position, means for operating said locking mechanism from its locking position to its unlocking position prior to movement of said switch from its one extreme position to its other extreme position by said manually operable means, means actuated by a train approaching the switch in a trailing direction

tion when the switch occupies its one extreme position for operating said locking mechanism from its locking to an unlocking position until after the train has completely trailed the switch, and means controlled by said star block for preventing said locking mechanism from moving to its locking position in the event the switch is moved to said one extreme position from its other extreme position by a train trailing the switch.

18. The combination with a railway switch of a mechanism connected with said switch and comprising, in combination, manually operable means for throwing the switch between its two extreme positions, locking mechanism biased to a locking position and effective to lock the switch for facing point moves over the switch, means for moving said locking mechanism to an unlocking position when a train trails the switch, an electromagnetic latch, means for energizing said latch when a train trails the switch, and spring means controlled in part by said latch and normally effective to bias the switch to a selected extreme position but effective when the switch is moved away from the selected extreme position by a trailing train for biasing the switch to and holding it in its opposite extreme position as long as said latch remains energized.

19. The combination with a railway switch of a mechanism connected with said switch and comprising, in combination, manually operable means for throwing the switch between its two extreme positions, locking mechanism constantly biased to its locking position and effective when in its locking position for locking the switch in one extreme position, means actuated by a train approaching the switch in a trailing direction when the switch is locked in said one extreme position for actuating said locking mechanism to unlock the switch until after the train is completely past the switch, means for moving said locking mechanism to its unlocking position prior to movement of said switch from its one extreme position to its other extreme position by said manually operable means, an electromagnetic latch, means for energizing said latch whenever a train trails the switch, spring means connected with said switch by means controlled in part by said latch and normally effective to bias the switch to a selected extreme position but effective when the switch is moved away from the selected extreme position by a trailing train for biasing the switch to and holding it in its opposite extreme position as long as said latch remains energized, and means for preventing said locking mechanism from moving to its locking position when said switch is moved to one only of its two extreme positions by a train trailing the switch.

HERBERT L. BONE.
